ELECTRICAL SET-UP MECHANISM

Chauncey L. Calkins, Chicago, Ill., assignor to
Lothar A. Ederer, Chicago, Ill.

Application March 16, 1934, Serial No. 715,905

3 Claims. (Cl. 177—380)

My invention relates to apparatus for electrical communication and particularly to the construction of apparatus for arranging and setting up messages, comprising a plurality of characters, which messages may thereafter be transmitted electrically.

One object of my invention is to provide a suitable, compact arrangement of dials, switches, and the like for the purpose of arranging and setting up messages. Another object of my invention is to provide a suitable assembly and housing of novel construction for such message set-up apparatus. Another object of my invention is to provide a simple arrangement of dials and observation windows which will permit a relatively large number of such dials to be used in close proximity for the purpose of arranging and setting up messages of considerable length, also of providing a construction which will facilitate the designating of the characters used and the interpretation of code symbols.

For the purpose of illustration of my invention I have shown various views of an example of such apparatus referred to as a sub-station dispatcher, capable of handling two messages, each comprising any permutation and combination of twelve characters. It will be understood that, although a complete showing is made of this particular apparatus, a variety of other arrangements are possible incorporating the novel and advantageous features of the construction which will in nowise depart from the spirit of the invention. Therefore, this showing is to be considered in a sense as diagrammatic.

Figure 1 shows a front elevation of such a message set-up apparatus;

Figure 2 shows a side elevation of such an apparatus;

Figure 3 shows a sectional elevation along the line 3—3 of Figure 1, through a message set-up apparatus;

Figure 4 shows a detail of the multiple electric contact plugs, taken along the line 4—4 of Figure 3;

Figure 5 shows a plan view in detail of the dial and switch assembly;

Figure 6 shows an elevation of the same assembly, with the operating knobs omitted;

Figure 7 is a section along the line 7—7 of Figure 6, illustrating the operating buttons and switches;

Figure 8 shows an enlarged section along the line 8—8 of Figure 5, illustrating the electric set-up switches, mounted on the rear member or insulated contact plate;

Figure 9 shows an enlarged detail section along the line 9—9 of Figure 8 of one such switch;

Figure 10 shows a plan view of the character window panels; and

Figure 11 shows a section along line 11—11 of Figure 10 of this panel.

Like characters will indicate like parts throughout the specification and drawings.

Referring now to Figures 1 and 2, A is a housing, preferably of sheet metal, covering the entire apparatus. A¹ is a metallic window panel holding the individual window strips shown as A² in Figure 10. A³, A⁴ are studs, preferably of rubber or other soft material, upon which the apparatus rests. A⁵, A⁶ are hook latch devices for holding the housing A to a base plate A⁵. Upon the base plate A⁵ is mounted certain internal framework consisting of vertical members A⁶, diagonal or sloping members A⁷ and A⁸, and short vertical front supports A⁹. Projecting through the front window panel A¹ are a series of dial and switch operating knobs A¹⁰ and A¹¹. Also mounted upon this panel is a signal lamp glass cap A¹², a call button A¹³ and a reset button A¹⁴, which buttons are used by the operator for calling the central station or other point to which the sub-station dispatcher is connected and for clearing or resetting certain electrical mechanism within the sub-station dispatcher and at other points.

Referring now to Figure 3, carried upon the vertical supports A⁶ are two groups of relay banks B and B¹. Mounted upon the base A⁵ is an impulse generating apparatus, not shown in detail, which automatically sends or transmits the message set up upon the apparatus as a series of groups of electrical impulses. C¹ is an operating magnet associated with the impulse generator. Carried upon the sloping supports A⁷, A⁸ are two banks of manually operated electric switches D and D¹. Apparatus of each such switch is arranged around a central shaft d shown in bank D, and correspondingly, d¹ in bank D¹. The series of knobs A¹⁰, A¹¹ are attached to these series of switch shafts in their respective banks, and a series of dials, one of which is indicated as d² in bank D and d³ in bank D¹, are attached to their respective series of shafts.

Referring to Figure 4, F and F¹ are multiple electric junction blocks, also found in Figure 3 in duplicate as at F² and F³, for the upper switch assembly D. These junction blocks are positioned to mate with their respective multiple plug elements F⁴, F⁵, F⁶, and F⁷, which are attached to the switch banks, the first two upon bank D and the second two upon bank D¹.

Referring now to Figures 5, 6 and 7, the construction of the switch bank D^1 alone will be described. The bank D is an exact duplicate of D^1 . The mechanism of this dial and switch bank is carried upon two main plates E , E^1 . Plate E rests and is secured upon the sloping framework members A^8 as shown in Figure 3. The plates E and E^1 are spaced and rigidly held in position by the spacing studs e and locking nuts e^1 threaded upon the reduced end portions e^2 . Passing through the plates e , spacers e^3 are placed about the studs e . A series of signal lamp sockets e^5 are carried upon the angle members e^7 attached to the plate E^1 . These lamps receive current through the electrical supply cable e^8 . The electric cable e^8 also carries current to the various switch points of the switches in the assembly in connection with multiple plug terminals F , F^1 . Within the signal lamp sockets e^5 are a series of illuminating lamps e^{10} . The series of small shafts and dials of which d^1 and d^3 are examples, shown in Figure 3, is clearly shown in Figures 5 and 6. It will be noted that successive dials overlap, shown, for example, where dial d^4 overlaps the dial d^3 making possible very compact and close arrangement of the character bearing dials. Upon these dials are inscribed any convenient number of characters d^6 , such as the digits from one to zero, or letters of the alphabet. These characters may be arbitrarily chosen and are arranged for convenient showing in the appropriate windows, and are so positioned as to register with the cam positions and related switch points of the switches attached to the shafts common to each dial and switch sub-assembly. The entire series of knobs A^{11} is connected in like manner to a series of small shafts upon which similar dials are mounted.

E^3 is a leaf switch actuated by the button A^{14} comprising the leaves e^{12} and e^{13} . E^4 is a leaf switch actuated by the button A^{13} comprising the leaves e^{14} and e^{15} . E^5 is a signal lamp bracket containing the signal lamp e^{16} which is so positioned as to light the glass A^{12} in the window panel A^1 . These switches and the signal lamp receive electrical energy through the cable e^8 .

Referring now to Figures 8 and 9, which show details of the dial and switch assembly, the knob A^{10} attached to the shaft d^1 will be recognized from previous description, as will the dial d^3 . d^9 is a collar which serves to provide a rigid mounting of the dial d^3 upon the shaft. A set screw d^{10} locks the dial in any desired position. The dial d^3 bears one more character space than the total number of characters, as shown in Figure 6; for example, each dial except the last dial in each group bears ten characters and one blank space; likewise, each switch contains ten contact points and one blank space. However, the last switch in each group contains eleven contact points, the dial bears ten characters and one blank space. The eleventh contact point on the last switch in each group is a part of the control circuit, which acts co-operatively to stop the impulse generator after the sending of the message. d^{11} is a multiple cam provided with a plurality of lobes equally spaced and corresponding in number to one more than the number of characters upon the dial d^3 . This cam is rigidly attached to a collar d^{12} which in turn may be set upon the shaft by a small set screw d^{13} . Acting upon this cam is a roller stop mechanism comprising a lever d^{14} journaled about a stud e carrying a roller d^{16} upon a pin d^{17} which is held

in engagement with the cam by means of the spring d^{18} . It will be noted that the spring d^{18} is common to two such roller stops acting upon adjacent cams. Clamped against a shoulder of the collar d^{12} by a clamp nut d^{19} are two sprung leaf wiper fingers d^{20} and d^{21} . These spring leaf contacts are insulated from the shaft d and collar d^{12} by the insulating washers and sleeve d^{22} and d^{23} . These spring leaves are in contact with each other and the shorter leaf d^{21} rides continuously upon a contact ring d^{24} which receives current from an electric connection d^{25} . The leaf d^{20} rides upon a series of contact buttons d^{26} .

Referring now to Figures 10 and 11, the window panel plate A^1 will be recognized from previous description, as will the individual window and designation strips A^2 , A^2 . Lying immediately under the panel A^1 are suitable transparent facings or windows a , a^1 covering the entire open panel spaces. Behind these transparent facings are the paper or celluloid strips A^2 , A^2 upon which appropriate designations may be inscribed. These strips are arranged in this manner to permit ready and quick changes in the designations adapting the machine to quick transfer from one class of service to another only with a minimum of change. These designation strips are provided with a plurality of windows a^3 . These windows a^3 are so arranged as to register with similar positions of each character bearing dial and to expose but one character at a time. This assembly of transparent facing and designation strips is held to the main plate A^1 by clamping plates a^7 and a^8 , readily removable to permit changing of the strips A^2 , A^2 .

The particular novel and useful features of my apparatus and the functioning of parts are as follows:

The apparatus shown is of a type used as a sub-station dispatcher of an electrical intercommunication system including a central switchboard and a number of points from which messages are to be sent. For example, such apparatus is especially adapted for use in control of operations in a factory where a central switchboard is located in the superintendent's office and the substation dispatchers are located near the various machines or at points where processes are carried out upon which reports must be made. Such reports may obviously include practically every variety of message between an operator and a foreman or superintendent, provided the apparatus is sufficiently adaptable and can deal with a sufficient number of characters. This particular apparatus has been adapted to take care of either of two messages comprising any arrangement of ten characters in twelve positions, or of one message in two parts consisting of any arrangement of ten characters in twenty-four positions. In the design of the apparatus the particular requirement of simplicity has been kept in mind since such apparatus must be available for use by unskilled help, and in this particular construction further provision for accuracy, namely, that the message shall be visible in complete form before sending and shall thereafter be sent entirely automatically at high speed, has been provided. The apparatus to accomplish these complicated processes has been so arranged in this invention to occupy a relatively compact housing having a sloping face readily readable in which in a small space twenty-four windows are located, together with twenty-four knobs by means of which dials, each bearing ten characters, will be readily visible.

or any other convenient number of characters, are turned until the proper character appears beneath the window immediately adjacent the knob manipulated. For the operator to send a message his procedure is to turn the knobs, say of the row marked A¹¹, until under each small window a³ shown in strip A² of Figure 10, the character appears which in the position in which it stands will form a proper part of the message to be sent. To facilitate the message sending, an unlimited variety of codes may be used, and special provision is made in this apparatus for the selection and arrangement of such codes and for the designation of the meaning represented by characters appearing in certain windows, and also by the construction of the window, quick change is possible from one system to another. For example, in Figure 10 certain sections of the windows may be grouped together and the characters appearing within these groups will then refer, for example, to a machine number in the first group, to a job number in the second group, to an operation number in the third group, and in the fourth group to the status of the operation. Of course, it is obvious that an unlimited variety of messages and compound messages may be sent by this apparatus. Previously, such intercommunicating systems have been extremely limited in the character or variety of messages which may be sent. The apparatus herein described has been especially developed to permit a practically unlimited variety of message transmission without decreasing materially either the size or space occupied by the general class of such transmitting equipment. The workman having set up a desired message, the characters having been checked as they appear in the windows, he then presses the button A¹³ which, through electrical circuits not here shown, signals a central station. The central station responds that it is ready to receive a message, this being indicated by a flashing of the light A¹². Thereupon the workman presses button A¹⁴ and the message which he has arranged upon either bank of knobs and dials will then be automatically transmitted through electrical circuits not here shown as they have no bearing upon the constructional features of the apparatus. During the automatic transmission of the message which is accomplished by the apparatus shown positioned B, B¹ and C within the housing, the workman is apprised of the fact by the lighting of the lamps e¹⁰. This particular apparatus is so arranged that the automatic transmission ceases upon the completion of the message arranged upon one bank of dials. Electrical provision is made for such messages to be called for electrically by the central station. This apparatus with its actuating button and switch is not shown and forms no part of the construction herein described.

The construction of the apparatus throughout has been with a view to compactness, lightness, and strength of parts, together with accessibility and easy assembly and departs from common practice to attain these ends. The entire frame is made of the lightest metal members possible, compatible with the relatively heavy loads to be supported and these in turn are tightly and easily sealed in a light metal housing cover. Since such apparatus is subject to severe handling and used and moved from time to time around a shop, and often by unskilled workmen, it must be extremely substantial in construction. Therefore the conventional wooden cabinet is entirely unsuited. Since such apparatus must be readily accessible

to inspection, it is a highly important feature to have sub-assemblies readily removable, though, when mounted, held with the necessary rigidity not only to protect the mechanism from breakage, but also to insure protection against the slight dis-alignments which often cause mis-function in such relatively delicate parts. It will be noted that to accomplish this purpose the switches and knobs are arranged in two separate, very compact sub-assemblies provided with matching multiple 5 plugs and sockets which permit these assemblies to be placed in and removed from sockets in the main framework, where they may be held with the greatest rigidity and where upon insertion all necessary electric contacts are made by multiple plugs 10 and sockets, and yet where the sub-assemblies when out of the frame are accessible from all sides and where each part may be reached for inspection or repair. The arrangement of the shaft, knob, dial, positioning cam, and switch is 15 such that any single unit may be readily dis-assembled for replacement of parts, and provision is made for accurate positioning of the dial and adjustment or setting in place of the locating cam 20 and switch. 25

Special consideration has been given the construction of the designating strips containing the windows through which the characters appear. The holder for these strips is so arranged as to permit a change to be made by the loosening of 30 a few screws. When this holder is loosened, the old designating strip with the windows cut therein is removed and a new strip inserted, which makes possible an immediate change from one 35 code or message arrangement to another. Also, a change in mechanism, which is usually necessary in such intercommunicating apparatus when a different message system is to be used, is avoided by the construction described. 40

I claim:

1. In combination in a message sending apparatus, a plurality of manually adjustable switches, each comprising a rotary member, a handle for rotating it, and a character member, a housing for said switches, shaped to provide an opening 45 dimensioned to expose all of said character members, and a removable indicating card, removably positioned within said opening, said indicator card provided with individual openings, one for each of the character members desired to be seen, and 50 provided with designating indicia adjacent said openings.

2. In combination in a message sending apparatus, a plurality of manually controlled switches, each switch including a shaft, means for rotating 55 it, and a positioning cam upon each said shaft, pivotally mounted positioning levers, one for each cam, said levers arranged in pairs and on opposite sides of said switch shafts, the levers of each pair being pivoted at opposite ends with their respective free ends positioned to contact the cams on adjacent shafts, and a single spring member attached to adjacent levers intermediate the ends thereof to maintain the free ends of said levers in 60 operative contact with the respective cams. 65

3. In combination in an electric set-up mechanism, a plurality of banks of multi-contact switches, each switch including a shaft carrying a character-bearing member, means for setting each switch individually, electric contacts for said 70 switches, a multi-point cam disc secured to each of said switch shafts and means for positioning each of said cams accurately to secure proper positioning of a character and to secure accurate electrical contact, each of said cam positioning 75

means including a pivotally mounted lever, said levers being arranged in pairs with the levers of each pair disposed on opposite sides of the switch shafts and pivoted at opposite ends, the free ends of said levers being positioned to contact respectively adjacent cams of adjacent switch shafts,

and spring means disposed between the shafts and attached to said levers intermediate the ends thereof to resiliently urge said levers into engagement with said cam.

CHAUNCEY L. CALKINS.
